UNITED STATES PATENT OFFICE.

EDGAR W. CLEVELAND, OF GRAND RAPIDS, MICHIGAN.

ADJUSTABLE ARM FOR MULTIPLE-SPINDLE DRILLS.

1,082,009.

Specification of Letters Patent.

Patented Dec. 23, 1913.

Application filed August 29, 1913. Serial No. 787,287.

To all whom it may concern:

Be it known that I, EDGAR W. CLEVELAND, a citizen of the United States of America, residing at Grand Rapids, in the 5 county of Kent and State of Michigan, have invented certain new and useful Improvements in Adjustable Arms for Multiple-Spindle Drills; and I do hereby declare the following to be a full, clear, and exact description of the invention, such as will enable others skilled in the art to which it 10 appertains to make and use the same.

My invention relates to improvements in
adjustable arms for multiple spindle drills,
and its object is to provide an arm which
is simple in construction, effective in opera-
tion, and on which the spindle bearing may
be quickly and easily adjusted, and to pro-
vide the device with various new and useful
features hereinafter more fully described
and particularly pointed out in the claims.

In multiple spindle drills, a plurality of drill supporting arms are clamped to a common head and each arm carries at one end a vertically adjustable journal box in which is journaled a drill spindle, these spindles all being connected by a suitable means to a common prime mover by which they are rotated. The drills mounted in the spindles are not always the same length, and furthermore it is often desirable to drill holes different depths and for this purpose the journal boxes carrying the spindles are vertically adjustable on the arms. It is also desirable to provide means by which these journal boxes may be quickly and easily adjusted and, as the drill spindles are often adjusted very close together it is necessary to have the journal box adjusting means accessible when so adjusted.

I have in this invention attained the aforementioned desirable features by constructing a drill supporting arm with a vertically adjusted journal box thereon and simple accessible means for quickly adjusting the same substantially as shown in the accompanying drawings illustrating an embodiment of my invention, in which:—

50 Figure 1 is an elevation of the upper portion of a multiple spindle drill showing a plurality of drill supporting arms embodying my invention, in operative position thereon; Fig. 2 is an inverted plan view of a portion of the same; Fig. 3 is an enlarged 55 sectional elevation of the preferred form of a drill supporting arm embodying my in-

vention, removed from the machine; Fig. 4 is an inverted transverse section of the same on the line 4—4 of Fig. 3; Fig. 5 is a sectional elevation of a portion of a modified form of my device; Fig. 6 is a transverse section on the line 6—6 of Fig. 5; Fig. 7 is a sectional elevation of another modification of the same; and Fig. 8 is a transverse section on the line 8—8 of Fig. 7.

Like numbers refer to like parts in all of the figures.

1 represents the frame of an ordinary multiple spindle drilling machine, on which is mounted a head 2 having T slots 3 in its under side. 70

4 is an adjustable arm provided with a longitudinal slot 5 through which a bolt 6 passes, said bolt having a T head within the key slot 3. By means of this bolt 6 the arm 4 may be clamped in any desired position against the under side of the head 2. 75

In the preferred form of my invention illustrated in Figs 3 and 4, a journal box 7 having the drill spindle therein is vertically so slideable on a tongue and groove way provided at one end of the arm 4. The end of the arm which carries the journal box is provided with two vertically extending slots 8, and two studs or bolts 9 and 10 projecting from the journal box extend through the said slots 8, one stud being in each slot. Engaging the inside surface of the end of the arm 4 is located a lever 11 having a fulcrum point near its middle and between the slots 8. This lever preferably has slotted or bifurcated ends which embrace the respective studs 9 and 10. The ends of the said studs are threaded and provided with nuts 9^a and 10^a adapted to engage the respective ends of the lever 11, and when tightened

ends of the lever 11, and when tightened the journal box 7 is firmly clamped against the end of the arm 4. The depth of the arm 4, to obtain the necessary strength and rigidity, must be so great that the upper 100 stud 9 and the nut 9^a must be located well within the central opening through said arm, thus making them inaccessible for ordinary adjustment, but the lower stud 10 and its adjusting nut 10^a project through 105 the lower portion of the end which is extended below the body of the arm and in this position the said nut may be readily engaged by a wrench or like tool. It will be obvious that the operation of this one 110 nut is all that is necessary to tighten or loosen the strain on both studs, as any pres-

sure brought to bear upon the lower end of the centrally fulcrumed lever 11 will be transmitted to the stud engaged by its opposite end and the strain on the studs 5 equalized.

The modified construction illustrated in Figs. 5 and 6 differs from the one described only in the location of the fulcrum of the lever 11. In this construction the fulcrum 10 consists of a pin 12 which extends through the central part of the lever and projects oppositely beyond the said lever to engage vertically extending shoulders 13 on the interior of the arm 4 and are adjustable on the 15 same.

Figs. 7 and 8 illustrate another modified form of clamping means in which the lever 11 is pivotally connected by the bolt 14 to the arm 4 and has no vertical movement. In 20 this construction T bolts 15 take the place of the studs 9 and 10 and extend through the end of the arm 4, their heads being located in a vertical T slot in the journal box 7. These bolts, as in the other forms are respectively extended through opposite ends of the lever 11 and are provided with nuts to engage said lever and clamp the journal box in place.

It will be obvious that in any one of the 30 above described forms of my invention it is only necessary to operate the lower nut 10^a to either clamp or release the journal box 7 so that it may be vertically adjusted to the desired position, and as this lower nut 10^a projects below the body of the arm 4 in each 35 form it is always accessible and may be readily and quickly adjusted.

What I claim is:—

1. An adjustable arm for multiple spindle 40 drills, comprising an arm, a journal box vertically adjustable on the end of the arm, a lever opposite to the box and fulcrumed intermediate its ends, and studs or bolts connecting the ends of the lever and the box to 45 secure the box in place or release the same for adjustment by operating one only of said studs or bolts.

2. An adjustable drill supporting arm, 50 comprising an arm having a vertical opening therethrough, a vertical way on one end of the arm, a journal box carrying a drill spindle vertically adjustable on said way, studs projecting from said journal box through the end of said arm, a centrally 55 fulcrumed lever within the opening in said

arm having ends to receive said studs, and nuts on said studs to engage the ends of said lever.

3. An adjustable drill supporting arm, 60 comprising an arm having a vertical opening therethrough, a vertical way on the outside of one end of said arm, said way having vertical slots therethrough, a journal box carrying a drill spindle and vertically adjustable on said way, two studs projecting from said journal box through said slots in the way, a vertically adjustable lever within the said opening and having a central fulcrum and also having bifurcated ends respectively embracing said studs, and nuts 70 on the studs to engage the ends of the lever.

4. An adjustable drill supporting arm, 75 comprising an arm having a vertical opening therethrough, a vertical way on the outside of the end of said arm, said way and end having two vertical slots therein, a journal box carrying a drill spindle vertically adjustable on said way, two studs projecting from said journal box through the respective slots and adjustable therein, a 80 lever within the opening in the arm and having a central fulcrum engaging the end of the arm between the slots and also having its ends bifurcated to embrace the respective studs, and nuts on said studs to engage the 85 respective ends of the lever.

5. An adjustable drill supporting arm, 90 comprising an arm having a vertical opening therethrough and having one of its ends extended downward below the body of the arm, a vertical way on the outside of the said extended end of the arm, said way and end having two vertical slots therethrough, one of said slots being located in the extended portion of the end, a journal box adjustable 95 on said way and carrying a drill spindle, two studs projecting from said journal box through the respective slots in the end of the arm, a lever having a central fulcrum engaging the inner surface of the arm between 100 the slots, the ends of said lever being bifurcated to embrace the respective studs, and nuts on said studs to engage the respective ends of the lever.

In testimony whereof I affix my signature 105 in presence of two witnesses.

EDGAR W. CLEVELAND.
